Alvin P. Wand and Homer W. Tennyson,
St. Louis, Mo.

Application January 16, 1947, Serial No. 136,182

Term of patent 3½ years

(Cl. D45—4)

To all whom it may concern:

Be it known that we, Alvin P. Wand and Homer W. Tennyson, both citizens of the United States, residing in the city of St. Louis, State of Missouri, have invented a new, original, and ornamental Design for a Bracelet, of which the following is a specification, reference being had to the accompanying drawing, forming a part thereof.

In the drawing:

Fig. 1 is a top plan view of a bracelet showing our new design,

Fig. 2 is a side elevational view of the bracelet, and

Fig. 3 is an edge view thereof.

We claim:

The ornamental design for a bracelet, substantially as shown.

ALVIN P. WAND.
HOMER W. TENNYSON.
